WILBUR S. LEWIS, OF CLEVELAND, OHIO, ASSIGNOR TO THE NESTLE-LE MUR COMPANY, OF CLEVELAND, OHIO, A CORPORATION OF OHIO

APPARATUS FOR FORMING PERMANENT WAVES

Application filed September 2, 1925. Serial No. 53,972.

This invention relates to apparatus and the method employed for forming permanent waves in the human hair.

In forming permanent waves in the human hair, it is general practice to first treat the hair with a softening solution, after which it is divided into strands and wound spirally upon rods and tied. The wound strands of hair are stretched while on the rods, and are covered with pads of absorbent material. Either before or after the pads are applied a hair treating solution, consisting usually of borax or oil, either in liquid or solid form, is applied around the strands, and when the solution is in solid form the hair is moistened. After the hair has been thus prepared a casing generally in the form of a fabricated tube is secured to encase the treated hair and a clamp is applied around the tube, adjacent the scalp, to prevent the solution when heated from running to the scalp. The exterior end of the tube is left open so that when the solution is heated, by placing heaters around the tubes, the steam and hot vapors can escape at a point removed from the scalp. The application of the heaters around the tubes liberates the gases and vapors of the solution and they act upon the hair, whereupon it will remain in the stretched and coiled condition in which it is secured upon the rods.

When the steam and vapors are permitted to escape from the ends of the tubes removed from the scalp, the thinner portion of the strands is subjected to the greatest amount of the vapor and gas, and likewise the thicker portion of the strand adjacent the scalp is subjected to the least amount of vapor and gas. It will be readily understood that it is more essential that the thicker ends of the strands of hair require a greater amount of impregnation than the thinner ends, to be treated in an equal degree.

An object of my invention is to provide a casing in which the gases and vapor are forced to escape from adjacent the thick end of the strand encased therein, so that the strand of hair will be acted upon proportionately to the thickness, and to provide a novel closure for the end of the casing remote from the scalp of the patient.

A further object of my invention resides in a tube for encasing a strand of hair during the heating operation in a permanent waving process.

These and other objects, and the invention itself will appear in the following detailed description.

In the drawings, Figure 1 is a side elevational view of an embodiment of the invention applied to a strand of hair; Fig. 2 is a side elevation of the tube and heater removed from the strand of hair; Fig. 3 is a similar view with portions of the tube and heater shown in section; and Fig. 4 is a longitudinal section of the tube applied to a strand of hair prepared to be heated.

Referring now to the drawings by characters of reference, 10 represents a strand of human hair which has been gathered from the scalp to be waved. The strand of hair is coiled around a rod 11, one end of which is provided with a saw cut 12 and the other end 13 of which is flattened to provide a finger grip. A string 14 is passed through the saw cut in the end of the rod adjacent the scalp and is tied around the strand of hair, thereby securing it to the rod. The coiled hair is then stretched lengthwise while the rod is held stationary and is then secured in such stretched coiled condition on the rod by the string 15 which is tied around the outer end. The hair preferably is treated with a suitable softening solution prior to the stretching and coiling operation.

After the strand has been secured upon the rod, it is preferably moistened with a lotion and is then covered by a strip of absorbent material 16 which is preferably cloth material and wound spirally around the strand. The cloth is preferably treated with borax or oil and is also dampened either before or after it is applied around the strand.

A fabricated casing is then applied to enclose the coiled strand of hair which has been prepared for the heating operation. The casing is preferably formed prior to its application, however it could be formed when applied, and preferably consists of a sheet of linen paper 17 rolled and sealed in tubular form, and a cup shaped closure member 18

which is inserted in one of the open ends of the tube and sealed to the inner wall thereof. The closure member is formed preferably of sheet linen paper and is annular and of substantially the same external diameter as the inner diameter of the tube. The other end of the tube is open and apertures 19 are provided in the tube adjacent thereto for purposes hereinafter set forth.

10 The open end of the casing is placed over the rod 11, and the casing is moved axially to a position adjacent the scalp, so that it encloses the coiled portion of the strand of hair and the covering 16. A heat resisting washer 20, preferably formed of felt, is placed around the strand of hair adjacent the scalp, and a clamp 21 is applied around the open end of the paper casing to seal such end thereof annularly against the strand of hair, intermediate the rod and the washer. A 15 tubular heater 22 is then applied exteriorly of the paper casing and around the portion thereof within which the hair is located which has been prepared for waving.

20 It will be seen that the scalp is protected from the heater by the washer 20, and that the hot lotion and contents of the tube can not burn the scalp because they are sealed in the tube by the clamp 21. The application of the 25 heat exteriorly of the casing will be transmitted to the preparation with which the hair within the casing has been treated, whether such preparation is applied with the wrapper 16 or directly to the hair, and the 30 wrapper 16 or directly to the hair, and the 35 vapors and gases liberated by the heat from the preparation material will permeate the coiled stretched hair and act thereupon to retain it in its deformed condition. Due to the fact that the ends of the casing are sealed, 40 the gases, vapor and steam must escape from the apertures 19 which are adjacent the thickest diameter of the coiled strand. It will thus be seen that the thicker portion of the coil will receive the greatest amount of the gases 45 and vapor which is necessary in order that such portion will be acted upon in an equal degree to the thinner portion of the strand.

With the casing I have provided only one 50 clamp is necessary to entirely encase the strand of hair, and when the tube becomes brown, which the operator can readily observe, it will indicate that the solution with which the hair has been treated has become dry. This manner of having such knowledge 55 eliminates any guessing as to the condition within the casing and prevents burning or heating of the hair to such an extent that it becomes brittle. With the method described herein, the varying thickness of the strand 60 will be acted upon proportionately by the gases and vapors to provide a uniform condition thereof when the waving process has been completed and hence the hair adjacent the head will receive a better wave, and a 65 uniform wave will be produced.

I do not claim broadly the provision of a container comprising the tube having an aperture through its wall close to the scalp, the tube being otherwise substantially closed during the heating process, as this is the subject of the joint invention of myself and John Charles Murray, and claimed in our joint Patent No. 1,611,466, dated Dec. 21, 1926, but I elect to claim herein the structural elements of my improved casing comprising the closure for the end of the tube remote from the scalp and the same in combination with a tube having its end disposed nearest the scalp apertured for the escape of steam and/or vapors which may be produced in the 70 casing during the so-called "steaming operation" of a hair waving process.

Various changes can be made in the design of the tube and the process of forming a wave herein described without departing 85 from the spirit of the invention and the scope of what I claim.

What I claim is:—

1. A tubular casing for enclosing a strand of hair prepared for the application of heat to form a wave, comprising sheet paper in its side walls, a cup shaped closure member insertable in one end of said tube in sealing engagement with the inner wall thereof, means for said tube adapted to seal its other end against the strand of hair operated upon adjacent its thickest portion nearest the head of the patient, said tube having an aperture adjacent its said other end to permit gases and vapors to escape from the interior of the 90 casing only from adjacent the thickest portion of the hair strand.

2. A tubular casing for enclosing a strand of hair prepared for the application of heat to form a wave, comprising sheet paper in its side walls, a cup-shaped closure member insertable in one end of the said tube in sealing engagement with the inner wall thereof, means for said tube adapted to seal its other end against the strand of hair operated upon adjacent its thickest portion nearest the 95 head of the patient.

3. A container for use in permanently waving hair comprising a flexible tube, a closure sealing one end thereof, the other end being deformable to close the same about a strand of hair, and an aperture adjacent to the latter end and sufficiently far therefrom to permit said collapsing between the end and aperture.

In testimony whereof, I hereunto affix my signature.

WILBUR S. LEWIS.
